[57] CLAIM

The ornamental design for a lighter, as shown and described.

DESCRIPTION

FIG. 1 is a top plan view of a lighter showing our new design;

FIG. 2 is a front elevational view thereof;

FIG. 3 is a side elevational view taken from the left of FIG. 2;

FIG. 4 is a side elevational view taken from the right of FIG. 2;

FIG. 5 is a bottom plan view thereof;

FIG. 6 is a front elevational view of a second embodiment, the only difference being the surface treatment of the lighter.

FIG. 1

FIG. 3

FIG. 2

FIG. 4

FIG. 5

FIG. 6
